UNITED STATES PATENT OFFICE.

ARTHUR H. OTIS, OF CLEVELAND, OHIO.

ELEVATOR-DOOR-OPERATING APPARATUS.

1,210,680.

Specification of Letters Patent. Patented Jan. 2, 1917.

Application filed October 4, 1915. Serial No. 53,977.

To all whom it may concern:

Be it known that I, ARTHUR H. OTIS, a citizen of the United States, residing at Cleveland, in the county of Cuyahoga and State of Ohio, have invented certain new and useful Improvements in Elevator-Door-Operating Apparatus, of which the following is a specification.

My invention relates to improvements in devices for operating elevator doors or gates.

The object of my invention is to simplify and cheapen such devices and at the same time insure positive operation of the doors under all conditions.

The devices are electrically operated and means are provided to prevent the opening of a door until the elevator is adjacent to the door to be opened. Means are also provided for automatically closing the door in case the operator should fail to close the door before leaving the landing.

Each elevator shaft is provided with a motor for operating a main cable which can be controlled from the car for opening or closing any one of the doors of the elevator shaft.

Other objects of my invention will be pointed out in the detail description to follow.

My invention is illustrated in the accompanying drawings wherein:

Figures 1 and 2 show the mechanism and circuits for controlling the operation of the elevator doors. Fig. 3 is an end view of the plate for carrying the clutch mechanism. Fig. 4 is a modification of Figs. 1 and 2.

Referring to Figs. 1 and 2, the elevator doors are shown at D and D¹, with their respective clutching mechanisms shown at S and S¹. The clutching mechanism is mounted on a plate 25. This plate is grooved on its under surface to engage the guide 99 and also grooved on its upper surface to allow the block 14 free movement in an upward and downward direction. This block 14 forms a part of the cable 12 which is controlled by the motor M. There is one of these blocks for each door and each block serves to present sufficient surface to be gripped by the clutching mechanism. The clutching mechanism is controlled by the solenoid 15. In operating the solenoid plunger 16 draws in the two jaws 19 and 20, which are fastened to the pivoted points 23 and 24 of the arms 18. These arms are pivoted or hinged to the brace 22 at the point 21 and also hinged or pivoted to the plunger 16 at the point 17. The brace 22 is fastened to the plate 25. As the plunger of the solenoid is drawn downward the points 23 and 24 move in and cause the jaws 19 and 20 to grip the block.

The plate 25 which carries the clutching mechanism is attached to the cables 200 and 220 as shown. The cable 200 passes around a pulley 202 fastened to a brace 201 in the elevator shaft. This cable then passes around the pulley 205 which is mounted in the bracket 203. This cable 200 is also attached to the elevator door at 206. One end of the cable 220 is fastened to the upper end of the plate 25 and the other end is fastened to the door after passing around the pulleys 204 and 208. When the plate 25 is lifted the cable 200 causes the door D to open.

The plate 25 and the clutching mechanism is of sufficient weight to cause the closing of the door when the jaws 19 and 20 disengage the block 14.

For each door there is an auxiliary clutch controlling mechanism as shown at E and E¹. Each one of these mechanisms consists of a movable cam 93 supported on the wall of the elevator shaft. The cam 93 is operated when the cam 84 belonging to the elevator is directly opposite and the foot lever X depressed. The device located within the car for controlling the clutch mechanism is shown at C. The depressing of the foot lever X causes the plunger 88 to ride on the cam 81 and carry with it the cam 84 which engages cam 93. The operation of cam 93 closes contacts 96 and 97 to allow the operation of the solenoid S.

The buttons 60 and 70 are located within the elevator under control of the operator for determining the direction in which the motor M shall operate to close or open the door. These buttons control the operation of the solenoids 30 and 40, which in turn connect the current to the motor M for determining its direction of rotation.

The motor M is provided with a threaded shaft shown at 3. This threaded shaft engages or carries with it a threaded collar 2 which moves when the motor rotates. The two guide rods 10 and 11 are provided for giving this collar 2 additional support. These rods are held in place by the brackets 8 and 9. The collar 2 is provided with an insulated button 5 which engages the contact springs 6 and 7. These contacts are

used in controlling the operation of the solenoids 30 and 40. When the collar 2 moves it causes the cable 12 to which it is attached to also move a corresponding distance. This cable 12 extends from the bottom to the top of the elevator shaft and at the top passes around the pulley 300. The end of this cable 12 is attached to a weight W supported by the guides G. For each door to be operated a block 14 is provided for allowing a gripping surface for the jaws 19 and 20.

In order to allow the elevator door to be locked a latch 210 is provided as shown. 15 This latch is operated by the clutch magnet 15.

Referring to Fig. 4, in place of a magnetic clutch for gripping the main cable I have shown a mechanical clutch. This 20 clutch is operated by the foot lever when the car is opposite the door to be opened. This foot lever causes the cam 184 to engage the roller 193 which is fastened to the rod 196. The operation of the rod 196 operates the 25 crank 197 which is rigidly fastened to the disk or segment 120. This segment is provided with gears as shown and which engage similar gears on the segment 119. These segments are provided with two raised cams 30 318 and 319 through which the main cable normally freely passes. When however, the rod 196 is depressed the two segments 119 and 120 turn and the surfaces of the cams 318 and 319 engage or grip the main cable.

35 The method of controlling the operation of the motor M is identical with that of Fig. 1.

I will not attempt to illustrate or describe any particular mechanism for operating the elevators. The devices for controlling the 40 doors can be applied to hydraulic, electric or other types of elevators well known in the art.

The operation of the devices shown in Figs. 1 and 2 is as follows. When the operator 45 wishes to open a particular door he waits until the car is opposite or adjacent to the door or landing, and then presses the foot lever X causing the cam 84 to engage with cam 93. As soon as these two cams 50 engage to operate the contacts 96 and 97 the circuit of the clutch magnet 15 is completed by the following path: negative source of current supply, 55, 54, cam 93, contacts 97 and 96, spring 98, winding of magnet 15, 55 51, 50, to the positive source of current supply.

The operation of the magnet or solenoid 15 causes the jaws 19 and 20 to grip the block 14 of the main cable 12. The operator 60 then presses the button 60 thereby completing the circuit of the solenoid 30 by the following path: positive source of current supply, 50, 51, contacts of button 60, 61, contacts 62, 63, winding of solenoid 30, 64, contacts 6, 65, 55, to the negative source of

current supply. The operation of the solenoid 30 completes the circuit of the motor M by the following path: positive source of current supply, 50, 51, 31, 32, 33, 52, motor M, 53, 36, 35, 34, 54, 55, to the negative 70 source of current supply.

The operation of the motor causes the shaft or threaded portion 3 to revolve thereby causing the collar or sleeve 2 to travel away from the motor. As the clutch solenoid 15 is now operated and the jaws 19 75 and 20 engaging block 14 of the main cable 12 it follows that the solenoid and all its component parts mounted on plate 25 travel with and in the same direction with the 80 main cable which is in an upward direction. The main cable moves in an upward direction due to the weight W. As soon as the clutch mechanism starts to travel with the main cable the door of the car is gradually 85 opened. After the button 60 is depressed and released the circuit of the solenoid 30 remains completed as the positive source of current supply remains connected to the winding of solenoid 30 by the following 90 path: positive source of current supply, 50, 51, 31, 32, 37, to the winding of the solenoid 30.

When the door is fully opened the button 5 on the sleeve 2 engages the contacts 6 95 thereby breaking the circuit of the solenoid 30 causing the motor to cease operating and consequently preventing further operation of the elevator door. (In the drawings the collar 2 is shown in its extreme position). 100

When it is desired to close the door the foot lever X is released thereby breaking the circuit of the clutch magnet 15 and causing the jaws 19 and 20 to disengage from the block 14. The releasing of the lever 105 40 also completes the circuit of the solenoid 40 by the following path: positive source of current supply, 50, 51, contacts 72, which are now closed, 73, winding of solenoid 40, 74, contacts 7, 65, 55, to negative source of 110 current supply.

The operation of solenoid 40 reverses the current supply to the motor M by the following path: positive source of current supply, 50, 51, 41, 42, 43, 53, motor M, 52, 46, 115 45, 44, 55, to the negative source of current supply. The operation of the motor in a reverse direction causes the sleeve 2 to move toward the motor and draws with it the main cable 12. The circuit of the solenoid 120 40 remains energized as the positive source of current supply is connected to its winding by the following path: positive source of current supply, 50, 51, 41, 42, 47, to the winding of solenoid 40. When the button 125 5 engages contacts 7 the circuit of the solenoid 40 is broken thereby disconnecting current from the motor M and causing it to cease operating. As soon as the clutch solenoid 15 is released it and its component 130

parts mounted on the main plate 25 travels in a downward direction thereby causing the elevator door to close.

In case the operator should keep the clutch 5 operated and start the car, no ill effect will be produced; for as soon as the cams 84 and 93 disengage, the clutch mechanism is automatically released and the door will close even after the elevator travels to another landing.

By providing the two buttons 60 and 70 the operator is enabled in case of emergency to operate the motor to cause the cable 12 to change from one position to another.

For purpose of illustration we will assume 15 that door D is to be opened and that the apparatus is in the position shown in Figs. 1 and 2 (the doors closed and the sleeve 2 in the position shown) and contacts 72 fail 20 to operate the solenoid 40 to cause the reversal of the motor. By depressing the button 70 without operating the foot lever X causes the circuit of solenoid 40 to be completed and the motor to operate in a reverse 25 direction to bring the sleeve 2 in its position of rest with the button 5 engaging contacts 7.

When the operator depresses the foot 30 lever the clutch mechanism operates and the motor M rotates to cause the sleeve 2 to travel until the button 5 engages contacts 6. In a similar manner the operator can de- 35 press button 60 and cause the sleeve 2 to assume a different position by operating the motor in a reverse direction. In this event the foot lever X will be depressed to sever the contacts 72. From this arrangement it will be noted that the operator can at will reverse the position of the main cable 12 and 40 the sleeve 2 to which it is attached.

The operation of the device shown in Fig. 4 as to the motor control is the same as described in connection with Figs. 1 and 2. Instead of providing a magnetic clutch for 45 gripping the main cable blocks I use a mechanical clutch which directly grips the main cable.

When the car is opposite the door to be 50 operated the foot lever is operated thus bringing the cam 184 into engagement with the roller 193. Pressure upon the foot lever causes the arm or rod 196 to turn the crank arm 197. The operation of the crank arm causes the segments 119 and 120 to turn and 55 the disks or cams 318 and 319 to grip the main cable.

As soon as the main cable is gripped the plate 125 moves upward or downward depending upon whether the door is to be 60 opened or closed. The plate in traveling carries with it the arm 196 causing the roller 193 to ride on the cam 184. The cam 184 is of sufficient length to cause the complete operation of the door in either direction. 65 When the roller 193 disengages the cam 184

the grip on the cable ceases. The cable blocks 14 (Figs. 1 and 2) can be omitted and the jaws 19 and 20 adjusted to directly grip the cable 12.

While I have illustrated and described the 70 motor as being located at the bottom of the shaft, the conditions can be reversed and the motor located at the top of the shaft.

In Fig. 2 I have shown means for locking or latching the doors. Each plate 25 or 75 clutching mechanism will be provided with a latch 210 shown in Fig. 2. This latch is pivoted to the plate 25 at 213. The end of the latch 211 normally engages notches 212 in the guide 99 and prevents the opening of 80 the door. The core of the solenoid 15 is provided with the extension rod 214, the end of which carries a knob 215. When the solenoid is operated by the operator pressing the foot lever X the knob 215 engages 85 or rides on the cam 216, causing the end of the latch to disengage the teeth 212.

While I have shown my invention applied to doors of the sliding type, it naturally follows that it is also applicable to doors which 90 are raised and lowered.

Having thus described my invention, what I desire to secure by Letters Patent is:

1. In an apparatus of the class described, 95 an elevator-car, a plurality of doors arranged at different landings, a common controlling means extending to said landings, a motor for operating said common means, an electro-magnetic clutch for each door, means for operating said clutch to grip said common controlling means when the car is adjacent to the particular door to be operated, and means for starting said motor in either direction to move the operated clutch to operate the particular door. 100

2. In an apparatus of the class described, 105 an elevator-car, a plurality of doors arranged at different landings, a common controlling means extending to said landings, a motor for causing the operation of said common means, an electro-magnetic clutch for each door, means for operating said clutch to grip said common controlling means when the car is adjacent to the particular door to be operated, and means rendered operable after the operation of said clutch for controlling the direction of operation of said motor to move the operated clutch to open or close the particular door. 115

3. In an apparatus of the class described, 120 an elevator-car, a plurality of doors arranged at different landings, a common controlling means extending to said landings, a motor for operating said common means, an electro-magnetic clutch for each door, 125 means for operating said clutch to grip said common controlling means when the car is adjacent to the particular door to be operated, means comprising a contact device individual to said elevator car for thereafter 130

- starting said motor to operate the particular door, and means for automatically disabling the motor operating means after the particular door is operated, said disabling means being controlled by the operated door.
4. In an apparatus of the class described, an elevator-car, a plurality of doors arranged at different landings, a common controlling means extending to said landings, a motor for operating said common means, an electro-magnetic clutch for each door, means for operating said clutch to grip said common controlling means when the car is adjacent to the particular door to be operated, means for thereafter starting said motor in one direction to open said door, and means for operating said motor in a reverse direction to close said door.
5. In an apparatus of the class described, an elevator car, a plurality of doors arranged at different landings, a common controlling means extending to said landings, a motor for operating said common means, an electro-magnetic clutch for each door, means for operating said clutch to grip said common controlling means when the car is adjacent to the particular door to be operated, means for starting said motor to open said door, means for starting said motor in a reverse direction to close said door, and means for automatically closing said door in case of failure to operate said motor to close said door.
6. In an apparatus of the class described, an elevator-car, a plurality of doors arranged at different landings, a common controlling means for said doors, a motor individual to and for operating said common means, an electro-magnetic clutch for each door, means for operating said clutch to bring it in engagement with said common controlling means when the car is adjacent to the particular door to be operated, contacts associated with and operated by said clutch-operating means, means controlled through said contacts for placing said motor in operation to open said door, and means also controlled through said contacts for operating said motor to close said door.
7. In an apparatus of the class described, an elevator-car, a plurality of doors arranged at different landings, a common controlling means for said doors, a motor individual to and for operating said common means, an electro-magnetic clutch for each door, means for operating said clutch to engage said common controlling means when the car is adjacent to the particular door to be operated, electro-magnetic means for operating said motor in one direction to open said door, and electro-magnetic means for operating said motor in a reverse direction to close said door.
8. In an apparatus of the class described, an elevator-car, a plurality of doors ar-
- ranged at different landings, a common controlling means for said doors, a motor individual to and for operating said common means, an electro-magnetic clutch for each door, means for operating said clutch to engage said common controlling means when the car is adjacent to the particular door to be operated, electro-magnetic means for operating said motor in one direction to open said door, electro-magnetic means for operating said motor in a reverse direction to close said door, and means for disabling said operating means for said motor when said doors are fully opened or closed.
9. In an apparatus of the class described, an elevator-car, a plurality of doors arranged at different landings, a common controlling means for said doors, a motor individual to and for operating said common means, an electro-magnetic clutch for each door, means comprising a set of contacts for operating said clutch to engage said common controlling means when the car is adjacent to the particular door to be operated, a switch for starting said motor in one direction to open said door, a second switch for operating said motor in a reverse direction to close said door, both of said motor operating means being controlled through the contacts of said clutch operating means.
10. In an apparatus of the class described, an elevator-car, a plurality of doors arranged at different landings, a controlling cable extending to said landings, a motor provided with a threaded shaft, a collar engaging said shaft and attached to said controlling cable for operating it, an electro-magnetic clutch for each door, means for operating said clutch to grip said cable when the car is adjacent to the particular door to be operated, means for operating said motor to move the operated clutch to operate the particular door.
11. In an apparatus of the class described, an elevator-car, a plurality of doors arranged at different landings, a controlling cable extending to said landings, a motor having a threaded shaft provided with a collar for moving said cable, an electro-magnetic clutch for each door, means for operating said clutch to grip said cable when the car is adjacent to the particular door to be operated, means for thereafter starting said motor to operate the particular door, and means controlled by said collar for disabling the motor operating means after the particular door is operated.
12. In an apparatus of the class described, an elevator-car, a plurality of doors arranged at different landings, a controlling cable extending to said landings, a motor having a threaded shaft and carrying a collar to operate said controlling cable, an electro-magnetic clutch for each door, means for operating said clutch to grip said cable

- when the car is adjacent to the particular door to be operated, means for thereafter operating said motor in one direction to open said door, means for operating said 5 motor in a reverse direction to close said door, and means controlled by said collar for disabling said motor operating means when said door is either fully opened or closed.
13. In an apparatus of the class described, 10 an elevator-car, a plurality of doors arranged at different landings, a controlling cable for said doors, a motor for operating said cable, a clutch for each door, means for operating said clutch to grip said controlling cable when the car is adjacent to the particular door to be operated, means for thereafter operating said motor in one direction to open said door, and means for operating said motor in a reverse direction to 15 close said door.
14. In an apparatus of the class described, 15 an elevator-car, a plurality of doors arranged at different landings, a controlling cable extending to said landings, a motor for operating said cable, a clutch for each door, means for operating said clutch to grip said controlling cable when the car is adjacent to the particular door to be operated, electro-magnetic means for operating said motor in one direction to open a particular door, and electro-magnetic means for operating said motor in a reverse direction to close said door. 20

In testimony whereof I affix my signature in presence of two witnesses.

ARTHUR H. OTIS.
